UNITED STATES PATENT OFFICE.

WICTOR A. GUSTAFSON, OF JOLIET, ILLINOIS.

TELEPHONE SYSTEM.

SPECIFICATION forming part of Letters Patent No. 606,285, dated June 28, 1898.

Application filed August 13, 1896. Renewed January 11, 1898. Serial No. 666,372. (No model.)

To all whom it may concern:

Be it known that I, WICTOR A. GUSTAFSON, a citizen of the United States of America, residing at Joliet, in the county of Will and State of Illinois, have invented certain new and useful Improvements in an Electric Telephonic Apparatus, of which the following is a specification, reference being had therein to the accompanying drawings, and the letters of reference thereon, forming a part of this specification, in which—

Figure 1 is a front elevation of the telephone apparatus. Fig. 2 is a side elevation of the same. Figs. 3 and 4 are detailed sectional views of the transmitter mechanism of the apparatus, showing, respectively, its two positions. Fig. 5 is a detailed side view of a portion of the transmitter-supporting arm of the apparatus and showing a lifting-spring applied thereto. Fig. 6 is a detailed sectional view of a portion of the transmitter of the apparatus, showing the manner of attaching and electrically connecting the binding-posts with the diaphragm thereof. Fig. 7 is a detailed cross-sectional view of the receiver-supporting lever of the apparatus, taken on a line immediately at one side of the hub thereof, showing the application of a spring to said hub. Fig. 8 is a sectional view of said lever-hub and of a switch-lever placed on the pivot-stud of said lever, showing the application of a combined tension and compression spring placed between said levers. Fig. 9 is a detailed side view of a portion of said receiverlever and its support. Fig. 10 is a detailed front view of the base portion of a push-button frame, showing the electric contact-plates thereof. Fig. 11 is a detailed view of the latch mechanism of the apparatus for holding the transmitter-arm extended, and Fig. 12 is a diagram of the secondary coil of the apparatus.

This invention relates to certain improvements in an electric telephone apparatus; and it consists in certain novel construction, arrangement, and combination of parts, which improvements are fully set forth and explained in the following specification and claims.

The object of this invention is to produce a simple inexpensive telephonic apparatus embodying in its construction an electric call

and electric sound transmitting and receiving devices so arranged and combined as to be automatic in breaking and making the bell-call circuit when the transmitting and receiving devices are brought into service and replaced out of service; and to accomplish the object sought I have employed common electric bell-calls, common electric telephone-receivers, novel electric telephone-transmitters, common secondary induction-coils, local batteries, push-button circuit making and breaking devices, and electric conductors arranged connecting said parts in the manner hereinafter described.

Referring to the accompanying drawings, I have illustrated but one apparatus; but, however, it will be understood that in service two or more stations are established and an apparatus placed at each station, the several apparatuses being electrically connected, and as the several apparatuses are constructed so as to be duplicates the illustration and description of one will be sufficient to fully convey to others the nature of my invention.

Referring to the accompanying drawings, A is a backboard, to which the several parts of the apparatus are attached and which is adapted to be secured to the side wall of a building or other convenient place, and thereby supported in a vertical position.

B represents a common electric bell-call device attached to the front side of said board, as shown. Above the said bell-call device is a horizontally-extending stud H', attached to said board by means of screws placed through screw-holes of its foot-piece H, and pivotally placed on said stud is a lever G, formed with a hook G'' at one end and with an enlarged hub G', which hub is made with an annular groove wherein a coil-spring J is placed, with one end thereof hooked into a hole in lever G, as shown in Fig. 1, and the opposite end of said spring is attached to a post J', as shown in Fig. 1 and more particularly in Fig. 7, which post is set in the board A. Said spring is for the purpose of yieldingly holding up the hooked end of said lever G to a limit governed by a keeper-hook L, attached to said board and inclosing the said lever adjacent to said hook G''. Said lever-hub G' is also chambered, as shown in section in Fig. 8, and sleeved on said stud H'. Back of said hub is

located a switch-lever S, and placed in said hub-chamber about stud H' is a coil-spring S', having one end hooked in a hole in the crown of said hub and having its opposite hooked end in a recess of said switch-lever, and in placing is given tension to yieldingly hold said switch-lever to one side from a vertical line against a stop-pin S², set in board A, and is also of sufficient length to yieldingly hold lever-hub G' a little distance off from said switch-lever, which distance is established by a cotter I, placed through a hole in the end portion of stud H', which holds said lever-hub seated on said stud, and said hub is also made with its end adjacent said cotter beveled each way from said cotter, so that said cotter rests in the hollow between said beveled faces when the lever S is in a horizontal position, as shown in Fig. 9, and at such times said switch-lever S is free from pressure enough, so its spring S' may throw it, as stated; but when the hooked end of lever G is either up or down its full limit the turned position of hub G' will cause said hub inclines to move under cotter I, and thereby force said hub against switch-lever S, and in so doing compress spring S', and thereby pinch the switch-lever S sufficiently hard, so it may then be moved to bring its free end to any position within the limits of its movement, and thus be held against the tension of the spring S', and when thus held perfect electric contact is insured between the stud foot-piece H and switch-lever S.

Attached to board A above lever G and on a radius from hub G are plates V, V', and V², which are so arranged that they may severally be in contact with the free end of switch-lever S, and electrically connecting each of said plates, respectively, is a line-wire, said wires being respectively shown at h, h', and h². The first plate V, however, is intended to be in connection with the main or principal line-wire h. Hence the said switch-lever is made to be automatically thrown to be in contact with plate V by means of its tension-spring, as described, so as to be constantly in circuit with said main line and to be temporarily in circuit with other subordinate lines h' h², connecting said plates V' V² by moving the switch-lever S to be in contact with said subordinate plates when it is desired, and thereby adapt the apparatus to be brought in circuit with lines other than what I have termed the "main" line.

To prevent too great movement of switch-lever S against the tension of its spring S', a second stop-pin S³ is set in board A, as shown in Fig. 1.

M represents a common telephone-receiver provided with an eye e, adapting it to be placed and hung on the hook G'' of lever G, and when thus placed on said lever will, by reason of its weight, hold said hooked end of said lever down to its full limit, as shown in Fig. 1. When said lever is thus turned down, the frictional contact between it and the

switch-lever S is relieved, and the spring S' then returns said switch-lever to contact with plate V of the main line h, so a call may be received. After a conversation the receiver is placed back on the hook of lever G. This will cause the switch-lever to automatically return to the terminal of the main line, as heretofore stated, so the operator is relieved from having to turn the switch-lever back to the terminal of the main line, thus leaving the switch in position so a call may be received from another station. This switch mechanism may be used on other kinds of telephones than the one described. The receiver is also provided with the usual electric conductors, (shown at R in Fig. 1,) the ends of which are respectively electrically secured in binding-posts P' and P², secured to board A.

C is a telephone-transmitter arranged below the call-bell, the case of which is made of non-conducting material mounted on the outer end of a metal arm D, hinged at its inner end by means of a cross-bolt E² to ear-lugs E' of a metal bracket E, which is secured to the board A by means of screws, as shown. In the bottom of the case of said transmitter is placed a metallic plate c'', as shown in Figs. 3 and 4, said plate being secured therein by means of a screw d, passing through a hole therein and extending through a corresponding hole in the bottom of said case and turns into the extending end of arm D, thereby electrically connecting said plate and arm. A carbon plate y is placed on the outer face of plate c'' and is secured thereto by means of screws b b. Said carbon plate extends to within a short distance of a diaphragm f of the transmitter and is provided with sockets on its face toward said diaphragm, said sockets being for the purpose of holding carbon balls a a, which, when the transmitter is in an upturned position, as shown in Figs. 1 and 4, will lie in said sockets, and thereby be out of contact with said diaphragm; but when said transmitter is in an extending or horizontal position, as shown in Figs. 2 and 3, said balls will roll partially out of their sockets, and thereby come in contact with said diaphragm. Said diaphragm is made of carbon and is held seated on the rim of the transmitter-case by means of a screw-cap C', having a central speaking-orifice in the usual manner and is electrically connected with a binding-post g'' at the side of said case by means of a copper plate g and screw g', as shown in Fig. 6.

E³ is a coil-spring sleeved on the hinge-bolt E² of arm D in a recess made in one side of said arm, as shown in Fig. 5. One end of said spring enters a hole of said arm, and its opposite end bears against a side-extending pin U of bracket E and in placing is given sufficient tension to yieldingly hold said arm D and transmitter C in an upturned position, as shown in Figs. 1 and 4, and when said arm is in such position a contact-point D' thereof will be brought in contact with a spring-plate Z, which is electrically connected with a bind-

ing-post W, which is supported by but insulated from bracket E by means of insulating-washers X and X', as shown in Figs. 3 and 4, and when said arm D is brought to an extending position, as shown in Figs. 2 and 3, said point D' will be disconnected from said plate Z.

Pivotedly connected to bracket E is a bell-crank latch F, made at one end with a beveled latch-piece F' and pivotedly connected at its opposite end with lever G through the medium of the non-conducting connecting-rod K, as shown in Fig. 1, and when the receiver M is removed from lever G and the spring J has caused the hooked end of said lever to be thrown up to a position opposite to that shown in Fig. 1 the said latch-lever will by gravity move so as to bring the latch F' thereof in line with the side of arm D, so that as said arm is moved to an extending position its heel portion will engage said latch and enter a side socket D'' of said arm, as shown in Fig. 11, and thereby hold said arm extended to substantially a horizontal position, as shown in Figs. 2 and 3, which position of parts will be maintained until the receiver M is again placed on lever G, when the weight of the receiver will bring down the hooked end of said lever, and thus raise its opposite end and lift rod K and release arm D and permit spring E³ to return said arm to its upturned position. (Shown in Fig. 1.) Attached to board A below said transmitter mechanism is a secondary induction-coil N, and below said coil is arranged a push-button frame O and contact-plates O' O² O³. Also attached to said board are binding-posts P P³ P⁴, which posts P³ P⁴ are electrically connected through the medium of conductors i i' with a battery Q. Binding-post P is for the connection of a ground-wire m and is electrically connected by means of a conducting-wire m' with contact-plate O'' of the push-button frame. Binding-post P' is electrically connected with conductor m', and hence with binding-post P and the ground-wire m by means of a conducting-wire m², shunted on said conductor-wire m'. Binding-post P² is electrically connected with one end of the secondary or induction coil N, the opposite end of said coil being connected, by means of a secondary wire n², with the foot-piece H and through the medium of said foot-piece with switch-lever S, and said coil-wire n' is also electrically connected with binding-post W of bracket E and the spring contact-plate Z thereof through the medium of a conducting-wire p, which is shunted on said conductor-wire n². Binding-post P³ is electrically connected with the bracket E direct by means of conducting-wire g and with one binding-post of the bell-call B by means of a conductor-wire g', and binding-post P⁴ is electrically connected with contact-plate O'' of the push-button frame by means of a conductor-wire r and is also connected with one end, t, of the primary coil of the secondary coil N, while

the opposite end, t', of said primary coil is electrically connected with binding-post g'' of the transmitter C, and the contact-plate O' of the push-button frame is, through the medium of a conductor-wire t², electrically connected with the opposite binding-post of said plate Z, all of which connections are fully shown in Fig. 1.

When in service, the receiving bell-call circuit is made as follows: The electric current comes in on a line-wire h through plate V, switch-lever S, foot-plate H, conductor-wire n² to conductor p, which is shunted on said wire n², thence through said wire p to the binding-post W of bracket E, through said post and spring contact-plate Z thereof to arm D, which arm is at such time held upright with its point D' in contact with said plate Z, thence through said arm to and through bracket E, thence through conductor-wire q to and through binding-post P³, thence through conductor-wire q' to the bell-call B, thence from said bell-call through conductor-wire t² to contact-plate O' of the push-button frame, thence through said plate to and through contact-plate O'', which two plates O' and O'' are so placed as to be in constant contact with each other, thence through conductor-wire m' to and through binding-post P, and from thence to the ground-wire m and off.

The transmitting call-circuit is as follows: Contact-plate O'' of the push-button frame being grounded through the medium of conductor-wire m', binding-post P, and wire m, and the contact-plate O'' being electrically connected with the battery Q through the medium of conductor-wire r, binding-post P⁴, and conductor-wire b, the circuit is made to the battery by pressing in the push-button O, which forces contact-plate O'' in contact with plate O''', and from the battery the circuit is made to the line-wire h through conductor-wire b', binding-post P³, conductor-wire q, bracket E, arm D, contact-plate Z, binding-post W, conductor-wire p, conductor-wire n², onto which wire p is shunted, foot-plate H, switch-lever S, and contact-plate V. The binding-posts P³ and P⁴ being electrically connected with battery Q, as stated, and the post P⁴ being the positive pole, the primary telephonic circuit is as follows: One end of the primary-coil wire is electrically connected with the said binding-post P⁴, and the electric circuit passes from said post to and through said primary coil to and through its opposite end t' to binding-post g'' of the transmitter C, thence through said post to plate g within the transmitter-case, and from thence to the transmitter-diaphragm f, which is in electric contact with said plate g. It will be understood that when using said circuit the transmitter C is turned down to a horizontally-extending position, as shown in Figs. 2 and 4, which causes the balls a to partially roll from their sockets and come in contact with diaphragm f, and from said diaphragm the current passes to and through said carbon balls a, thence

to and through the carbon plate y , thence to and through bottom plate C' , thence through plate-screw d to and through arm D , thence through bracket E to and through conductor-wire q to the binding-post P^3 , which is the negative pole of the battery, and the secondary telephonic circuit is as follows: The electric current comes in through line-wire h , thence through plate V , switch-lever S , conductor-wire n^2 , thence through the coil N , the ends of which are shown at n and n' , thence through binding-post P^2 , thence through one branch of conductor R to the telephone-receiver M , thence through said receiver and to and through the opposite branch of said conductor R to binding-post P' , thence through conductor-wire m^2 to and through conductor-wire m' to binding-post P , and thence to the ground and off.

20 As a means for preventing arm D from turning down too far and striking its heel portion against board A a buffer T is socketed in board A and arranged to extend sufficiently from the board so as to be engaged by the arm heel portion, as shown in Fig. 2.

25 Contact-plates V' and V^2 are arranged as shown for the purpose of connecting therewith the line-wires h' and h^2 other than the main-line wire h , which line-wires h' and h^2 I have 30 termed "subordinate" lines, intended for the purpose of connecting with other telephone-stations which may be brought into service by adjusting switch-lever S to register therewith at the will of the person at the principal telephone apparatus, which may be understood as the apparatus illustrated.

35 In operation, when the parts are in the position shown in Fig. 1 the call-bell B in a similar apparatus electrically connected with 40 the one shown may be operated to call at that end of the line by pushing on the push-button O , so as to bring the plates O' and O'' in contact with each other.

45 When it is desired to use the apparatus for speaking purposes, the transmitter C is turned down to the position shown in Figs. 2 and 3, and the receiver M is removed from the hook G'' on the outer end of lever G , by means of which the electric circuit between the call-bells is broken, and the electric circuit is established between the receiver and transmitter with those of a similar apparatus. (Not necessary to be shown.)

Having thus described my invention, what 55 I claim as new, and desire to secure by Letters Patent, is as follows, to wit:

1. The herein-described electric telephonic apparatus consisting of the combination of

the bell-call device, the push-button device, the telephone-transmitter, the telephone-receiver, the secondary induction-coil, the battery, the line-wire contact-plates, the switch-lever mechanism, the receiver-supporting lever and latch mechanism, the binding-posts and conductors, all arranged to operate substantially as and for the purpose set forth, wherein the telephone-transmitter is supported by means of a pivoted arm, and adapted to be turned out of or into service, and adapted when turned out of service to automatically break the primary telephonic circuit, and make the bell-call circuit, and when turned into service to automatically make the said primary circuit and break the bell-call circuit, substantially as and for the purpose set forth.

2. In the telephonic apparatus described, in combination with the circuit-conductors, the stud H' having the foot-plate H , the switch-lever S sleeved on said stud, the hooked lever G having the chambered beveled end hub G' sleeved on said stud, the tension-spring S' arranged in said hub-chamber and connecting said levers, the pin I placed through the end portion of said stud in the hollow between the bevel-faces of said hub, the coil-spring placed on said hub and attached at one end to said lever G and attached at its opposite end to a stationary post, substantially as and for the purpose set forth.

3. In the telephonic apparatus described the combination of the hinged transmitter-arm D having the side latch-socket D'' , the hooked lever G , bell-crank latch-lever F having the beveled latch-piece F' , and the non-conducting connecting-rod K , connecting said levers substantially as and for the purpose set forth.

4. In the telephonic apparatus described, the combination of the stud H' , the lever G and hub G' thereof having the beveled end, the switch-lever S , and the springs S' and J substantially as and for the purpose set forth.

5. In a telephone system, the combination of the oscillating lever G , the telephone-receiver adapted to be detachably connected to the end of said lever, the switch-lever S , the means for frictionally connecting said levers, and the means for returning said switch-lever to contact with the terminal of the main line substantially as and for the purpose set forth.

WICTOR A. GUSTAFSON.
